UNITED STATES PATENT OFFICE.

JAMES S. ROBINSON, OF JAMESTOWN, NEW YORK.

AUTOMATIC SHUT-OFF VALVE FOR GAS-SERVICE PIPES.

SPECIFICATION forming part of Letters Patent No. 379,128, dated March 6, 1888.

Application filed March 24, 1887. Serial No. 232,308. (No model.)

To all whom it may concern:

Be it known that I, JAMES S. ROBINSON, a citizen of the United States, residing at Jamestown, in the county of Chautauqua and State 5 of New York, have invented certain new and useful Improvements in Automatic Shut-Off Valves for Gas-Service Pipes; and I do hereby declare the following to be a full, clear, and exact description of the invention, such as will 10 enable others skilled in the art to which it app pertains to make and use the same.

This invention relates to automatic shut-off valves for use on gas service pipes; and it consists in certain improvements in the construction 15 thereof, as will fully appear from the following general description and claims.

In gas-distribution it often occurs, particularly in the distribution of natural gas, that the pressure ceases while the burner-cocks are 20 open, and then resumes before the cocks are closed, in which case the gas flows through the burner without being lighted, and of course escapes into the rooms, and may do great harm. The object of the valve here shown is to close 25 the pipes against further flow automatically if at any time the pressure in the pipes ceases. Shut-off valves for this purpose have been heretofore devised, my device being an improved construction.

30 My device is illustrated in the accompanying drawings as follows: Figure 1 is a longitudinal vertical section on the line $x-x$ in Fig. 4. Fig. 2 is an elevation view of the side plate A, showing the inside face of said plate. Fig. 35 3 is a like view of the side plate B, showing the inside face. Fig. 4 is a like view of the central plate, C, showing the face which is toward the plate A.

The valve-case is composed of three parts, 40 viz: first, a central plate, C, which is in the form of a disk, with connecting-nipples c' , and with a central depression or dish, which forms the chamber C', seen in Fig. 1, and it has also an entrance-port, c^2 , through the nipple 45 c , a port, c^3 , which is covered by the gate E, and an exit-port, c^4 , from the chamber C' or dish through the nipple c' ; second, an outside cap-plate, A, which has a protuberance which forms a chamber, A', over the valve E; third, 50 a second plate, B, which is dished to form the diaphragm-chamber B'. These plates are se-

cured together by screws or bolts in any desirable manner. There will be a packing between the plates C and A, which will be so cut away as to not interfere with the valve-chamber A', and a flexible or yielding diaphragm, D, will be clamped between the plates B and C. This diaphragm may be of rubber, leather, metal, or any of the many substances employed for that purpose.

55 In the center of the diaphragm D is secured a stem, D', which is provided with an eye, d , on the end within the chamber C'. This stem extends out through the opening B^2 in the wall of the diaphragm-chamber, so that it can be 60 manipulated when desired.

65 Of course various forms of valves may be used; but it is desirable to use a form that will work easy at all times, and I have shown a common hinged gate-valve, E. If the device 70 is to stand as shown in the drawings, the valve should be provided with a weight—like E', for example—to insure its seating properly; but if the device should lie horizontally, the left side in Fig. 1 being the upper side, there will 75 be no need of a weight. A rod, E², extends from the gate E through the port c^3 up to and through the eye d in the diaphragm-stem D'.

As shown in Fig. 1, the valve is closed. If 80 gas were turned on, none could pass through the device. To open a passage for the gas it is necessary to grasp the stem D' where it protrudes through the opening B^2 and draw on it, and thereby draw on the lever E², which will open the gate E, and thus admit the gas 85 to the chamber C' on the left of the diaphragm. Gas being once admitted to this chamber, the diaphragm D will be held deflected by the pressure of the gas, and the gate E will thus be kept open and a passage for gas will be 90 maintained. It will enter at c^2 , pass under the gate, through the port c^3 , thence through the chamber C', and out at the port c^4 . If the flow of gas through the device should stop from any cause, the diaphragm would be free to react 95 and the gate would close by gravity, and a resumption of the flow could not take place until the stem D is again drawn upon and the gate thus reopened.

The diaphragm D should be very flexible, 100 so that a low degree of pressure will be sufficient to keep it deflected and maintain the

valve open. The reaction of the diaphragm should not be depended upon to close the valve, because if it is the diaphragm would have to possess too much elasticity, and it would 5 not be kept deflected by a low degree of pressure.

What I claim as new is—

1. In a shut-off valve, the combination, substantially as set forth, of a valve-chamber having an inlet-passage, a second chamber having a flexible diaphragm and connected with the first chamber by a port, a valve automatically acting to positively close said port when the pressure is reduced and permit the diaphragm 15 to assume a vertical position, a stem connecting said diaphragm and valve and having a weighted end projecting into the valve-chamber, whereby a deflection of said diaphragm will hold said valve open, a stem extending 20 from said diaphragm outside of the valve-case in position to be operated upon to open said valve, and an exit-passage from said second chamber into the service pipe.

2. In a shut-off valve, the combination, substantially as set forth, of the central plate, C, 25 having nipples c c', passages c² and c⁴, and port c³, and a depression or dish formation, C', a valve, E, closing said port c³ and having a stem, E², passing through said port and lying within said dishing part C', a cap-plate, A, 30 having a valve-chamber, A', covering said plate C and valve E, a cap-plate, B, having a dished chamber, B', covering the dished chamber C', a diaphragm, D, clamped between said plates B and C, and a stem, D', extending from 35 said diaphragm through the plate B on one side of the diaphragm and connecting with the valve-stem E² on the other side of said diaphragm.

In testimony whereof I affix my signature in 40 presence of two witnesses.

J. S. ROBINSON.
